UNITED STATES PATENT OFFICE.

ROBERT HARDIE, OF ROME, NEW YORK.

STEAM-BRAKE.

SPECIFICATION forming part of Letters Patent No. 375,933, dated January 3, 1888.

Application filed March 24, 1887. Serial No. 232,223. (No model.)

To all whom it may concern:

Be it known that I, ROBERT HARDIE, of Rome, in the county of Oneida and State of New York, have invented a new and useful Improvement in Steam-Brakes for Locomotives and other Railway-Vehicles, of which the following is a specification.

Where brakes are applied to the wheels of locomotives by a suitable piston actuated by steam-pressure within a cylinder, the sudden discharge of exhaust-steam from the brake-cylinder is objectionable, in some cases to such an extent as to necessitate the running of the exhaust-pipe into the smoke-box to carry off the exhaust, and a spring is usually employed for releasing the brake or for making the return movement of the actuating-piston in a direction the reverse to that in which it is moved by fluid-pressure to put on the brake.

The object of my invention is to construct an apparatus so that the motive fluid after having performed its work in applying the brake will be employed in releasing the brake, thereby being employed in addition to the releasing-spring, or it may be in lieu of such a spring; also to prevent the sudden escape of the exhaust with a roar.

In carrying out my invention I employ, in combination with a brake and brake-applying connections of a railway-vehicle, a cylinder and a piston attached to said connections for operating them, the cylinder affording greater steam-space on one side of the piston than on the other, and having a constantly-open exhaust from the larger steam-space, and valve apparatus for controlling the admission of motive fluid to the smaller steam-space on one side of the piston, and for controlling the exhaust of such motive fluid to the larger steam-space on the opposite side of the piston. The piston may have a hollow trunk, whereby the difference in the fluid-space on opposite sides thereof is obtained, and the exhaust from the larger space may be through the hollow trunk.

The invention consists in novel combinations of parts, hereinabove referred to, and hereinafter described, and pointed out in the claims.

In the accompanying drawings, Figure 1 represents such portion of a locomotive and

my improved device secured thereto as is necessary to illustrate my invention. Fig. 2 is a sectional elevation, upon a larger scale, of the brake-applying cylinder. Figs. 3 and 4 are sectional views illustrating, upon the same scale as Fig. 2, one form of valve apparatus and connections which may be employed, showing the valve in two different positions; and Fig. 5 is an elevation of such valve apparatus.

Similar letters of reference designate corresponding parts in all the figures.

A A designate the adhesion or supporting wheels of a locomotive, and B B brake-shoes, which are hung by arms B' from rock-shafts B', and are thereby so supported as to permit of their swinging toward and from the wheels A. The several brake-shoes B (two being here represented) are actuated by a rod, C, and to this rod is connected a bell-crank lever, C', which is fulcrumed at c to a suitable portion of the locomotive-frame.

D designates a cylinder, and D' a piston working therein, and serving, when actuated by steam or other motive fluid, to apply the brake. As here represented, the steam or fluid spaces D² D³, below and above the piston D', are of different sizes or capacities, and if steam, after being admitted to the steam-space D² to force the piston D' upward, be exhausted into the larger steam space, D³, above the piston, a considerable diminution of pressure will occur. The piston D' I have shown as having a hollow piston-rod, D⁴, provided at the lower end with an outlet, d, governed by a valve or cock, d', and through which steam and the water of condensation may escape. In the hollow piston D' is an aperture, d², through which the space D³ above the piston communicates with the hollow piston-rod D⁴. The hollow rod D⁴ works through a suitable stuffing-box, d³, at the lower end of the cylinder D, and the piston is provided with suitable packing, d⁴.

E designates pipes, which lead, respectively, from the lower and upper ends of the cylinder D above and below the piston.

In order to properly operate the apparatus, it is necessary that there be provided a valve apparatus whereby steam may be admitted to the space D² below the piston, and whereby

the spaces D^2 D^3 may be placed in communication with each other. In the present example of my invention I have shown a simple plug-valve, F, in a suitable plug-seat, F', and 5 provided with suitable pipe-connections, f f' f'' f^3 . The pipe-connection f^3 , which constitutes the supply for steam or other motive fluid, leads from the boiler or other suitable reservoir, while the connections or branches 10 ff' communicate with the pipes E E'. I have represented the plug F as having formed in one side a port or passage, f^4 , by which the connection f' and the pipe E', leading to the upper end of the cylinder D, may be alter- 15 nately placed in communication with the pipe-connection f and pipe E, leading to the lower end of the cylinder D, or with the pipe connection f^2 , leading to the atmosphere. The 20 interior of the plug F is hollow, and has ports f^5 f^6 , which communicate with corresponding ports in the plug-seat, forming continuations of the pipe-connections ff^3 . The valve or plug F may be operated by a suitable handle, f^7 .

In the first operation of the apparatus, and 25 in order to apply the brakes B, the valve F is turned to the position shown in Fig. 3, thereby placing the upper end of the cylinder D in communication, through the pipe E' and pipe f^2 , with the atmosphere, and at the same 30 time placing the lower end of the cylinder below the piston D', and, through the pipe E and the supply f^3 and ports f^5 f^6 , in communication with the steam supply. The steam thus admitted below the piston D' raises said piston, and through the links c' , which connect 35 the piston-rod D' with the bell-crank lever C', applies the brakes B. When it is desired to release the brakes, the valve-plug F is turned to the position shown in Fig. 4, and by the 40 port or passage f^4 the pipes E E', which lead from the lower and upper ends of the cylinder D, are placed in communication, the supply of motive fluid from the pipe f^3 being at the same time shut off by the valve F. The 45 steam, which has performed its work in the steam-space D^2 below the piston, then passes through the pipes E E' and valve F F' into the

space D^3 above the piston. It is thereby reduced in pressure; but its force being exerted upon a larger area than the area of the lower 50 side of the piston, the said piston is forced downward and the brake is released. After the brake has been released the exhaust-steam escapes slowly from the upper steam space, D^3 , through the opening or aperture d^2 into 55 the hollow piston-rod D', and this steam, together with the water of condensation, slowly escapes through the outlet d' without any material noise. It will be understood that the port f^6 in the plug F and the corresponding 60 port or opening in the plug-seat are below or in a different plane from the ports f^5 f^4 .

What I claim as my invention, and desire to secure by Letters Patent, is—

1. The combination, with a brake and brake- 65 applying connections of a railway-vehicle, of a cylinder and a piston attached to said connec- 70 tions for operating them, the cylinder afford- 75 ing a greater steam-space on one side of the piston than on the other, and having a con- stantly-open exhaust from the larger space, and a valve apparatus for controlling the ad- mission of motive fluid to the smaller space on one side of the piston, and for controlling the exhaust of such motive fluid to the larger 80 space on the opposite side of the piston, sub- stantially as herein described.

2. The combination, with a brake and brake- 85 applying connections, of the cylinder D and the hollow trunk-piston D', affording the steam- 80 spaces D^2 D^3 , of different size, and the piston being attached to said brake-applying connec- 85 tions, and the piston also having an open- 90 ing, d^2 , from the space D^3 to the hollow trunk and the opening d from the trunk, and a valve apparatus for controlling the admission of motive fluid to the space D^2 and its exhaust from the space D^2 to the space D^3 , substan- tially as herein described.

ROBT. HARDIE.
